UNITED STATES PATENT OFFICE.

JACOB WOLF, OF FORT MADISON, IOWA.

IMPROVEMENT IN RAZOR-STROPS.

Specification forming part of Letters Patent No. 37,840, dated March 3, 1863.

To all whom it may concern

Be it known that I, JACOB WOLF, of Fort Madison, in the county of Lee and State of Iowa, have invented a new and Improved Metallic Razor-Strop; and I do hereby declare that the following is a full, clear, and exact description of the same, reference being had to the accompanying drawings, forming a part of this specification, in which—

Figure 1 represents a longitudinal vertical section of my invention. Fig. 2 is a plan or top view of the same.

Similar letters of reference in both views indicate corresponding parts.

To enable those skilled in the art to make and use my invention, I will proceed to describe its construction and operation with reference to the drawings.

A represents a plate of sheet-zinc, which is firmly secured to a frame or handle, B, formed similar to the handle of an ordinary razor-strop. Said frame may be made of a solid block of wood, and the plate A, which is fastened to it at its ends by tacks or screws *a*, or in any other desirable manner, may rest on its upper surface from end to end, or the frame may be hollowed out so as to form a case or receptacle for the razor, and the plate A may be attached to its top by means of a swivel or in any other suitable manner, so that it can be turned out of the way when it is desired to take the razor out or put it in. To the opposite side of the frame B an ordinary leather strop, C, may be attached.

In using my metallic razor-strop the razor is moved toward the cutting-edge, instead of moving it in the opposite direction, as is generally done in ordinary leather strops to prevent them getting cut by accident, awkwardness, or carelessness, and if the metal plate A is kept clean, its effect on said cutting-edge is much superior to that of ordinary leather strops, and the razor can be kept sharp and in good order without the aid of a stone, or any other means commonly used for this purpose. The metal plate A will last for many years, it is not liable to be cut in sharpening the razor, and its first cost will certainly not exceed that of an ordinary leather strop. The metallic plate is made of polished zinc, and its effect upon the blade of a cutting instrument is to produce a finer edge than any leather or elastic strop.

My improvement may be used dry, without oil or any moisture, and either the motion before mentioned, or that commonly given to the razor in sharpening it upon a strop or hone, may be employed.

Having thus described my invention, I claim and desire to secure by Letters Patent as an improved article of manufacture—

A razor-strop provided with a surface of polished zinc, as and for the purpose herein shown and described.

JACOB WOLF.
